UNITED STATES PATENT OFFICE.

ELMER B. GRUSH, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BREAST-SCOURING MACHINE.

Application filed December 12, 1917. Serial No. 206,774.

To all whom it may concern:

Be it known that I, ELMER B. GRUSH, a citizen of the United States, residing at Beverly, in the county of Essex and State of 5 Massachusetts, have invented certain Improvements in Heel-Breast-Scouring Machines, of which the following description, in connection with the accompanying drawings, is a specification, like reference characters 10 on the drawings indicating like parts in the several figures.

This invention relates to abrading machines and is herein illustrated as embodied in a machine for scouring the breasts of 15 heels of boots and shoes.

Ordinarily a rotary wheel of frusto-conical shape is used for performing this operation. With high-heeled shoes, however, the difficulty arises that it is impractical or 20 impossible to scour that portion of the breast of the heel which is adjacent to the shank of the sole by reason of the fact that the edge of the scouring wheel remote from the heel is liable to strike the shank of the sole 25 thereby either preventing the edge of the scouring wheel from operating upon the breast close to the shank or disfiguring the shank or producing both of these undesirable results.

30 In order to overcome this difficulty as well as to provide an improved machine for general use, one feature of the present invention comprises, in a machine of the class described, a frusto conical scouring tool open at the small end to receive the forepart of a shoe and having an outer abrasive surface 35 with a concave edge to conform substantially to the shank of the shoe and means for operating said tool. Conveniently the 40 scouring tool is in the form of a hollow frustum of a cone having a thin wall and adapted to permit the forepart of the shoe to be thrust through the small end of the frustum so that the breast of the heel may readily be 45 scoured up to its junction with the shank.

It is desirable that the work be protected from the abrading tool and from the dust generated by the abrading operation and another feature of the invention comprises 50 a fixed hollow guard to enclose part of the work and a rotary tool surrounding the guard for operating on the unenclosed part of the work. Conveniently the tool is enclosed by a blower casing except for an open-

ing to permit presentation of the heel of the 55 shoe and the tool is carried by the rotating vanes of a fan. There results a compact and efficient construction for scouring the breast of the heel and removing the dust.

These and other features of the invention, 60 including certain details of construction and combinations of parts, will be described as embodied in an illustrative machine and will be defined in the appended claims.

Referring to the accompanying drawings, 65

Fig. 1 is a side view, principally in vertical longitudinal section, showing a machine in which the present invention is embodied, a shoe being illustrated in position to have the 70 breast of its heel scoured;

Fig. 2 is a front elevation of the machine and the shoe;

Fig. 3 is a section in detail on the same plane as the section in Fig. 1 showing a portion of the scouring tool and a portion of the 75 shoe, the latter being shown in full lines;

Fig. 4 is an elevation of a part of the scouring tool;

Fig. 5 is a section on the line 5—5 of 80 Fig. 3, and

Fig. 6 is a section on the line 6—6 of 85 Fig. 3.

The casing 7 of the blower by which the dust is removed is formed in two parts 85 hinged together at 9 and held in the position shown by a spring latch 11 which is fastened by screws 13 to the immovable section of the casing and engages a pin 15 on the movable or swinging section. This movable section 90 is provided with an opening 17 to expose a portion of the scouring tool and has projecting from it into the axial space or chamber which is surrounded by the fan blades or 95 vanes 19 of the blower a hollow guard or shield 21 to receive the forepart of the shoe and thereby to protect it from the dust generated by the scouring or abrading operation. This shield serves another important purpose in that it guards against liability of injury by the vanes to that portion 100 of the shoe which necessarily enters said axial chamber. The outer ends of the vanes 19 are connected by an annular holder 23 having a countersunk portion to receive the 105 ring-shaped base of the frusto-conical scouring tool, said tool comprising a countersunk portion 25, a felt pad 27 located in the

countersink and an abrasive cover 29. A clamping ring 31 carried by bolts 33 which are threaded into the holder 23 is adapted to grip the abrasive cover and hold it firmly in place. Fig. 4 shows certain of these parts on a larger scale and illustrates how the ends of the cover overlap.

Referring to Fig. 5, it will be noted that the radius of curvature of the conical face 10 of the scouring tool is less than that of the breast of the heel, this proportion of parts being provided since a single tool is in practice used to scour heels the breasts of which have different radii of curvature. Turning 15 now to Fig. 6, it will be seen that the radius of curvature of the edge of the opening in the smaller end of the frusto-conical scouring tool is greater than that of the transverse curvature of the shank of the sole, this proportion of parts being provided in order that the localities at the base of the breast of the heel adjacent the corners thereof may be properly scoured. This relation of the curvature of the face of the tool and 20 of the opening in the smaller end of the tool to the curvature of the breast of the heel and that of the shank of the sole respectively is important since it makes possible the scouring of the whole breast of the heel and 25 at the same time greatly facilitates the scouring operation. To scour the breast, the operator merely presents the breast to the tool, as shown in Fig. 1, and then rocks the shoe slightly, first on an axis substantially 30 perpendicular to the shank of the shoe, and then on an axis substantially perpendicular to the breast of the heel, thereby presenting every part of the breast to the tool.

Although, as stated above, a single tool is 40 used to scour heels the breasts of which have different radii of curvature, it becomes necessary to remove the tool and replace it by one of different shape when heels are encountered the breasts of which differ greatly 45 in curvature. It has been explained above that the screw-bolts 33 act upon the clamping ring 31 to hold the abrasive cover in place. It should now be noted that these screw-bolts serve also to hold the tool in 50 place and provide ready means for making use of a plurality of interchangeable tools.

The direction of rotation of a scouring tool is indicated by the arrow in Fig. 2; and in order to aid the operator in holding the 55 shoe firmly in place with its breast in contact with the abrading face of the scouring tool, a rest 35 is provided, said rest having a stem which passes through a perforated lug 37 on the blower casing and is held in adjusted position by means of a thumb screw 39. This rest has a curved operative face to 60 permit sidewise rocking of the shoe in a path substantially perpendicular to the breast of the heel, as has been described 65 above.

In the operation of the machine the vanes with the tool attached are rotated in any suitable manner, as for example by means of the tight and loose pulleys 41, 43. The shoe is presented to the operating tool in the 70 manner illustrated in Fig. 1 and is rocked slightly first on an axis perpendicular to the shank of the shoe (this movement being permitted by the proportion of parts which is illustrated in Fig. 5) and second on 75 an axis which is perpendicular to the breast of the heel (this movement being permitted by the proportion of parts which is illustrated in Fig. 6). In this way the whole surface of the breast of the heel is thoroughly scoured. It will be noted that because of the peculiar shape of the scouring tool there is no difficulty in scouring the breast of the heel close to the shank of the sole, since there is nothing to strike the 80 shank of the sole and thereby disfigure the shank or interfere with the operation of the tool. It will be understood, of course, that the guard 21 is so shaped as not to touch the shank during the scouring operation, that is, 85 its shape is such as to present no obstacle to the manipulation of the shoe for the purpose of bringing the breast of the heel into proper position against the abrading surface of the tool. At the same time, the guard 90 serves to prevent contact of the shoe with the revolving fan vanes at all times, whether the shoe heel is being presented to the tool for operation or is being removed. The current of air drawn through the opening 17 100 passes out through the pipe 45 carrying the dust with it.

Although the invention has been set forth as embodied in a particular machine, it should be understood that the invention is 105 not limited in the scope of its application to the particular machine which has been shown and described.

Having thus described my invention, what I claim as new and desire to secure by 110 Letters Patent of the United States is:

1. A machine of the class described, having in combination, a frusto-conical scouring tool open at the small end to receive the forepart of a shoe and having an outer 115 abrasive surface with a concave edge extending entirely to the edge of the opening to conform substantially to the shank of the shoe, and means for operating said tool.

2. A machine for scouring the breast of the heel of a shoe, having in combination, a hollow conical abrasive member having a free and unobstructed space in its center adapted to receive the forepart of the shoe 125 with the heel breast against the abrasive surface of the conical member, a rotary shaft, and means mounted on the shaft and engaging the larger end of the cone to support it.

3. In a machine of the class described, a blower casing having a central hollow shield to protect the forepart of a shoe, fan vanes rotatable around the shield, and a hollow tool secured to the fan vanes and having a portion projecting through an opening in the casing.

4. In a machine of the class described, a blower casing, an annular series of fan vanes 10 rotatable near the periphery of the casing to leave an unobstructed central space to receive a portion of the work, and a hollow tool secured to the fan blades and having a portion projecting through an opening in 15 the casing.

5. A machine of the class described, having, in combination a hollow abrading tool for operating upon a part of a piece of work, means for operating said tool, and 20 means located within the hollow tool for protecting the remaining part of the work from the dust generated by the abrading operation.

6. A machine of the class described, having, in combination, a hollow abrading tool 25 through which the forepart of the shoe may be inserted, a hollow dust guard extending into the tool and in which the forepart of the shoe is held during the scouring operation, and means for operating said tool.

7. A heel breast scouring tool comprising a hollow frusto-conical, cover-supporting portion, a ring-shaped base fast to the larger 35 end of the frusto-conical portion, an abrasive cover, means co-operating with said base for fastening said cover in place, and rotary means fast to the base to support and rotate the tool.

8. A heel breast scouring tool in the form 40 of a frustum of a hollow cone open at both ends, the construction being such that the forepart of a shoe may be thrust through the frustum from the smaller end to present the breast of the heel of the shoe to the tool, 45 the conical abrasive surface extending to

the edge of the opening at the smaller end of the frustum.

9. A heel breast scouring tool comprising an annular, frusto-conical member open at both ends the radius of curvature of the 50 conical face thereof being less than that of the breast of the heel and the radius of curvature of the edge of the opening in the smaller end of the frustum being greater than that of the transverse curvature of the 55 shank of the sole of the shoe to which the heel is attached.

10. A machine of the class described having, in combination, an annular holder open at both ends to receive part of the work, a 60 hollow frusto-conical member, an abrasive cover for said member, and a common means for fastening the cover to the member and the member to the holder.

11. A heel breast scouring tool comprising a rigid member hollow and open at both ends to provide space to permit the forepart of a shoe to be thrust through it and having a thin wall to permit scouring of the breast of a heel close to the shank of the 70 sole of a shoe, a removable abrasive cover for said tool, means for fastening the cover in place, and means for rotating the tool.

12. In a machine of the class described, a blower casing having a central hollow shield 75 to protect the forepart of a shoe, and a hollow abrasive wheel rotatable around the shield and projecting through an opening in the casing.

13. In a machine of the class described, a 80 blower casing having a central hollow shield to protect the forepart of a shoe, fan vanes rotatable in the casing around the shield, and an abrasive wheel rotatable around the shield and projecting through an opening 85 in the casing.

In testimony whereof I have signed my name to this specification.

ELMER B. GRUSH.
